UNITED STATES PATENT OFFICE.

RALPH V. SAGE, OF PHILADELPHIA, AND GEORGE E. THACKRAY, OF WESTMONT BOROUGH, PENNSYLVANIA.

COMBINED SPRING CAP AND TRUCK BOLSTER COLUMN GUIDE.

Application filed October 31, 1921. Serial No. 511,340.

To all whom it may concern:

Be it known that we, RALPH V. SAGE and GEORGE E. THACKRAY, both citizens of the United States, and residents of the city of Philadelphia, in the county of Philadelphia, and the borough of Westmont, in the county of Cambria, respectively, and both in the State of Pennsylvania, have invented new and useful Improvements in Combined 10 Spring Cap and Truck Bolster Column Guides; and we do hereby declare the following to be a full, clear, and exact description of the invention, such as will enable others skilled in the art to which it appertains to make and use the same.

Our invention relates to the construction of bolsters for railway cars, and particularly to the end portions thereof, and we provide a member secured to and forming part of 20 the bolster, which serves as a top spring cap and spring seat for receiving and holding the springs and for transmitting the load from the bolster thereto, while integral extensions thereof form column guides for the 25 up and down movement of the bolster, which are adapted to contact with the columns of the truck side frame in order to maintain the bolster in position during its movement on the springs, and our construction 30 also provides a strengthening and stiffening member for the end of the bolster and serves to distribute the load properly over the end of the same.

Our construction is applicable to bolsters 35 of what is known as the bath-tub type, the lower parts of the end portions of which are narrower than the upper portions, but may also be applied to bolsters of any other types as may be readily understood.

Having thus given a general description 40 of our invention, we will now, in order to make the matter more clear, refer to the annexed sheet of drawings, which forms part of this specification, and in which like characters refer to like parts.

Figure 1 is a side elevation of a portion 45 of a truck side frame with the end of the truck bolster in one of its normal positions, illustrating the application of our invention; Figure 2 is a side elevation of the end portion of a bath-tub bolster with our improved spring cap and truck bolster column guide attached thereto; Figure 3 is a bottom plan view of the spring cap and truck 50 bolster column guide detached from the bol-

ster end; Figure 4 is a vertical longitudinal sectional elevation of the spring cap and truck bolster column guide taken on the line IV—IV of Figure 3; Figure 5 is a top plan view and Figure 6 is a side elevation 60 of our spring cap and column guide.

Referring now to the characters of reference on the drawings:—1 is a truck side frame which is shown of cast metal construction, but may be of any of the usual forms of truck side frames; 2 is the bolster illustrated of bath-tub type, but our invention may be applied to other types as well; 3 is our combined spring cap and truck bolster column guide as a whole; 4 are the bolster springs shown as a nest of five springs for high capacity freight cars, but we may adapt our construction to receive more or less springs; 5 are the truck columns of the side frame; 6 are the column guide portions of our construction which may be provided with flanged sides 7, and 8 are rivets which secure our combined spring cap and truck bolster column guide to the sides of the bolster. Lateral strengthening flanges 80 9 are also provided to strengthen and stiffen the column guides as illustrated near the bottom and similar flanges 10 are also provided near the upper portion. The lower surface of our combined spring cap and truck bolster column guide is provided with 85 spring pockets 11, which are surrounded by the downwardly extending flange 12 in order to provide a recess in which the upper ends of the springs are seated, and the flange 90 12 assists in holding them therein. We also further provide bosses 13 which extend downwardly from the spring seat and project within the central openings of the helical springs in order to further hold them 95 laterally in position. The spring cap illustrated is adapted to receive five helical springs, but its form or size may be modified to receive four, six or any number desired. We also provide holes 14 through 100 which rivets 15 pass to further secure our construction to the bottom of the bolster end. In order to further strengthen the structure we provide ribs or flanges 16 extending inwardly from the flat end portions 105 of the column guide, which, however, for the purpose of ease of construction and assembly, do not bear against the sides of the bolster, but at the same time stiffen the column guide portions. We also provide 110

other similar stiffening flanges 17 as illustrated.

The entire construction of our combined spring cap and truck bolster column guide 5 is made integral and preferably of one steel casting.

Our construction may be made of different widths to suit cars of various capacity and to receive any number of springs there- 10 for, while the bolster end to which it is applied may be of substantially uniform size, thus adapting the construction for use without materially changing the size of the bolster, as such change requires different and 15 costly pressing dies to form bolsters of different sizes, and this is obviated by our construction.

Although we have shown and described our invention in considerable detail, we do 20 not wish to be limited to the exact and specific details thereof as shown and described, but may use such modifications in, substitutions for, or equivalents thereof as are embraced within the scope of our invention or 25 as pointed out in the claims.

Having thus described our invention, what we claim and desire to secure by Letters Patent is:

1. The combination with a bolster, the 30 lower end portions of which are narrower than the upper portions of the bolster ends, of a spring cap and column guide secured to the end portion thereof, comprising a plate portion under the bolster end provided with 35 spring pockets in its lower surface and with integral column guides, said plate portions and column guides extending laterally from the bolster end.

2. The combination with a bath-tub bolster, the lower end portions of which are narrower than the upper portions of the bolster ends, of a combined spring cap and column guide mounted and secured on the end portion thereof and comprising an integral construction, including a bottom plate 45 provided with a spring recess and spring retaining bosses, column guides extending

outwardly and laterally therefrom, and strengthening flanges extending inwardly of said column guide portions.

3. The combination with a bath-tub bolster, the lower end portions of which are narrower than the upper portions of the bolster ends, of a spring cap and column guide secured and mounted on the end thereof, comprising a spring cap having a downwardly extending marginal flange adapted to surround the upper portions of the outer springs, a plurality of downwardly extending bosses adapted to be seated within the 55 spring openings to assist in retaining them in position, column guides extending outwardly and laterally from each side and provided with strengthening ribs, all formed integrally.

4. An integral combined spring cap and column guide mounted on and secured to the end of a bath-tub bolster, the lower end portions of which are narrower than the upper portions of the bolster ends, comprising a 70 substantially flat lower portion adapted to contact with the bolster end having a spring pocket on its lower surface of greater width than the lower portion of the bolster end and other integral laterally extending portions provided with grooves, and adapted to act as a column guide.

5. An integral combined spring cap and column guide secured to a bath-tub bolster end, comprising a substantially flat lower 80 portion, the upper surface of which contacts with the lower portion of the bolster end and is provided with a spring pocket on its lower surface surrounded by a marginal flange, and integral column guides extending outwardly and laterally thereof and provided with end grooves adapted to co-operate with the truck columns, and inner and outer strengthening flanges formed integral therewith.

In witness whereof we hereunto affix our signatures.

RALPH V. SAGE.
GEORGE E. THACKRAY.
